are inoculated with *Aspergillus niger* cells. Potato dextrose agar is also used as an artificial medium for *Aspergillus niger* cells and for *Penicillium italicum*. Emmons agar is used as the artificial medium for *Trichophyton mentagrophytes*. The Petri plates are held at either room temperature for one week or 30° C. for five days in order to allow the organisms to grow, at the end of which time the results are observed and noted. Table I contains the data obtained in this manner. The minimum inhibitory concentration for complete control is given for representative compound.

TABLE I.—IN VITRO PLATE TEST

Compound	Holding temp. (° C.)	Minimum inhibitory conc. 100% control (p.p.m.)		
		<i>A. niger</i>	<i>P. italicum</i>	<i>T. mentagrophytes</i>
3,4,6-trichloro- coumarin	Room temp.	15		
3,4-dichlorocou- marin	Room temp.	15		
3,4-dichloro-6- methylcoumarin	Room temp.	15		
3,4-dichloro-6- fluorocoumarin	30	1	1	5
3,4-dichloro-6- bromocoumarin	30	1	1	1
3,4,6,7-tetra- chlorocoumarin	30	5	10	5
3,4,6-trichloro-7- methylcoumarin	30	50	2 (50)	10
3,4,6,8-tetrachloro- coumarin	30	50	1	1
3,4,6-trichloro-8- methylcoumarin	30		5	10

¹ In nutrient agar.

² Partial control at this concentration.

The compound 3,4,6-trichlorocoumarin was also tested in Emmons agar against *Pullularia pullulans*. A similar method was employed, as described above, wherein the compound was incorporated in the dissolved agar and cells of the test organism were added to the solidified agar. The compound thus tested gave partial control of *Pullularia pullulans* at 5 p.p.m. 3,4,6-trichlorocoumarin was also effective in partial control of *Penicillium* at 5 p.p.m., complete control of bean rust at 1000 p.p.m. and 95% control of mildew on pinto bean plants at 1000 p.p.m.

EXAMPLE 2

Textile treatment test

In order to test the applicability of the present method of inhibiting microbiological development, cotton fabric was treated therewith and the resulting inhibiting effect investigated. The test was performed according to the following procedure.

The candidate compound was dissolved in sufficient acetone to give a 1% solution. From this solution was taken 0.5 ml. and this was added to 500 ml. of tap water to give a resulting concentration of 10 p.p.m. of the test compound in water. The solution of water and test chemical was agitated for a short period of time. Following the preparation of the rinsing solution the fabric samples were added. Four one-inch square pieces of 8 oz. white cotton duck was used as the test fabric. The fabric samples were agitated gently for five minutes in the test solution. All of the cloth samples were then removed and allowed to air dry until yet damp.

Sterile, melted and cooled nutrient agar was inoculated with respective selected test organisms by streaking the agar plates with cells of the organisms. Selected as representative test organisms were *Aspergillus niger* for fungi and *Staphylococcus aureus* for bacteria. The damp-dry treated fabric samples were placed on the inoculated agar and incubated.

When 3,4,6-trichlorocoumarin was used as the test compound in the above-mentioned test procedure, the test plate inoculated with *Aspergillus niger* cells was incubated at room temperature for three days, after which time a zone of inhibition of 21 mm. had formed around

the fabric sample. The nutrient agar plate inoculated with *Staphylococcus aureus* cells and containing a piece of treated cloth was incubated for 24 hours at 37° C., after which time a zone of inhibition of 6 mm. had formed around the treated fabric sample.

It should be noted that fabric samples containing thereon effective quantities of microbiostatic agent exhibited a zone of inhibition comprising an area surrounding the sample wherein bacterial growth was not observed.

10

EXAMPLE 3

Paint test

The test paint formulation is made up as follows:

15	Titanium dioxide, anatase chalking	g	12.5
	Co-fumed, 35% leaded zinc oxide	g	42.5
	Magnesium silicate	g	30.0
	Refined linseed oil	g	31.8
	Z-2 linseed oil	g	9.2
20	Mineral spirits	g	15.0
	Cobalt naphthenate, 6%	mg	200
	Manganese naphthenate, 6%	mg	100
	Lead naphthenate, 24%	mg	400

25 Sample of the above formulation is used as a control sample. In addition, a sample is prepared to which 300 mg. of 3,4,6-trichlorocoumarin is added. Each of the above samples is placed in separate 5½ oz. stainless steel mills each having 30 g. of ½" stainless steel balls added. 30 The mills are shaken on a paint shaker for 2½ hours. The paint samples are each of a Hegman gauge of 6. One milliliter sample from each of the prepared paints is painted on strips of fiberglass tape, ten inches by three-fourths inches and 0.007 inch thick, that are previously desized at 700-800° F. until all of the carbon was removed.

35 The paint strip samples are allowed to dry at room temperature for 2 weeks. At the end of this time each sample is cut into three parts. One part is soaked in running water for 72 hours. Another part is weathered in a weatherometer for 300 hours and the other part is used as a control. Each of the treated parts is cut into one inch long strips and placed on hardened steril ASTM nutrient salts agar (60 ml.) in large Petri dishes. Each dish is inoculated with a water suspension of *Aspergillus niger*, *Penicillium* sp., *Pullularia pullulans* and two unidentified cultures. The mixed cultures are incubated at 30° C. and 90% relative humidity and are examined at weekly intervals. The results are as follows:

50

TABLE II.—GROWTH OF FUNGI ON PAINT SURFACE

		1 week	2 weeks	3 weeks	4 weeks
55	Paint with no biocide:				
	Untreated strip	0	+	+	++
	Water soaked strip	+	0	++	++
	Weathered strip	0	+	+	++
60	Paint with 3,4-dichloro- coumarin:				
	Untreated strip	0	0	0	0
	Water soaked strip	0	0	+	+
	Weathered strip	0	0	0	+

0=No growth. + = Slight growth. ++ = Moderate growth. +++ = Heavy growth.

65

The concentration of a compound of the present invention, constituting an effective amount in the best mode of administration in the utility disclosed is readily determinable by those skilled in the art. Various changes and modifications are possible without departing from the spirit and scope of the invention described herein and will be apparent to those skilled in the art to which it pertains. It is accordingly intended that the present invention shall only be limited by the scope of the claims.

75

What is claimed is:

1. The method of controlling the growth of bacteria and fungi comprising applying thereto an effective amount of a compound having the formula

wherein R is selected from the group consisting of hydrogen, halogen and methyl and R₁ is selected from the group hydrogen and halogen.

2. The method according to claim 1 in which R is 6-chloro and R₁ is hydrogen.

3. The method according to claim 1 in which R is hydrogen and R₁ is hydrogen.

4. The method according to claim 1 in which R is 6-methyl and R₁ is hydrogen.

5. The method according to claim 1 in which R is 6-bromo and R₁ is hydrogen.

6. The method according to claim 1 in which R is 6-fluoro and R₁ is hydrogen.

7. The method according to claim 1 in which R is 6-chloro and R₁ is 8-chloro.

8. The method according to claim 1 in which R is 6-chloro and R₁ is 8-methyl.

9. A composition effective against bacteria and fungi comprising an inert aerosol bomb liquified gas having dissolved therein as the effective ingredient a compound having the formula

wherein R is selected from the group consisting of hydrogen, halogen and methyl and R₁ is selected from the group hydrogen and halogen.

10. A composition according to claim 9 in which R is 6-chloro and R₁ is hydrogen.

11. A composition according to claim 9 in which R is hydrogen and R₁ is hydrogen.

12. A composition according to claim 9 in which R is 6-methyl and R₁ is hydrogen.

13. A composition according to claim 9 in which R is 6-bromo and R₁ is hydrogen.

14. A composition according to claim 9 in which R is 6-fluoro and R₁ is hydrogen.

15. A composition according to claim 9 in which R is 6-chloro and R₁ is 8-chloro.

16. A composition according to claim 9 in which R is 6-chloro and R₁ is 8-methyl.

17. The method of controlling the growth of fungi in paint comprising incorporating therein a fungicidally effective amount of a compound having the formula

wherein R is selected from the group consisting of hydrogen, halogen and methyl and R₁ is selected from the group hydrogen and halogen.

18. The method according to claim 17 in which R is chlorine and R₁ is hydrogen.

19. The method of controlling the growth of fungi and bacteria upon cellulosic materials which comprises applying thereto an effective amount of a compound having the formula

wherein R is selected from the group consisting of hydrogen, halogen and methyl and R₁ is selected from the group hydrogen and halogen.

20. The method of claim 19 in which R is chlorine and R₁ is hydrogen.
